UNITED STATES PATENT OFFICE.

GUSTAVE JESSE, OF WRAY, COLORADO.

CHICKEN-BROODER.

1,209,444.

Specification of Letters Patent. Patented Dec. 19, 1916.

Application filed September 6, 1916. Serial No. 118,739.

To all whom it may concern:

Be it known that I, GUSTAVE JESSE, a citizen of the United States, residing at Wray, in the county of Yuma and State of Colorado, have invented certain new and useful Improvements in Chicken-Brooders; and I do hereby declare the following to be a full, clear, and exact description of the invention, such as will enable others skilled in the art to which it appertains to make and use the same.

This invention relates to a chicken brooder and has for its primary object the provision of a device of this character which will afford a hover for small chickens and which will keep the chickens thoroughly warm without the employment of artificial heat, obviating the expense and labor of running a heating system to heat the device to a correct degree of temperature.

Another object of this invention is to provide a cover supported in spaced relation to the ground or flooring of a building and having secured thereto and depending downwardly therefrom a plurality of tufts of feathers which chickens may hover or pass into and be protected from exposure, similar to hovering under a female fowl.

A further object of this invention is to secure the tufts of feathers in a circular row to the cover, whereby passages are provided between the rows of feathers, so that the chickens may pass into and out of the feathers at will and which affords efficient warmth to the chickens when hovering among the feathers.

A still further object of this invention is the provision of a chicken brooder of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a longitudinal sectional view of the chicken brooder, constructed in ac-

cordance with my invention, Fig. 2 is a top plan view of the same, and Fig. 3 is a plan view of the cover with the feathers removed.

Referring in detail to the drawing, the numeral 1 indicates a circular cover constructed from wood or suitable material and having secured thereto a plurality of legs 2 for supporting the cover in spaced relation to the ground or flooring of a building. The cover has a central recess 3 for the reception of a tuft of feathers. The feathers are preferably light feathers with the ends of the quills inserted within the central recess 3 and glued or otherwise secured therein. The cover 1 has a plurality of circularly arranged recesses 4 adjacent the periphery thereof for the reception of a plurality of tufts of feathers, the quill portions thereof being glued or otherwise secured within the recesses 4. The tufts of feathers secured within the recesses 4 and the tufts of feathers secured within the central recess 3 form a circular passage between the central tuft of feathers and the circularly arranged tufts of feathers whereby chickens may pass within the passage and hover between the feathers.

A plurality of feathers 5 are glued or otherwise secured about the periphery of the cover 1 and form a passage between the circularly arranged tufts of feathers for the reception of chickens. The feathers 5 are further secured to the periphery of the cover 1 by means of the metallic band 6 which is nailed or otherwise secured to the cover to prevent the quill portions of the feathers 5 from becoming detached and mutilated.

From the foregoing description taken in connection with the accompanying drawing, it will be noted that a device has been provided whereby the chickens may readily enter and exit from the feathers when desired and which will be thoroughly protected from exposure similar to hovering under a female fowl, obviating the requirement of artificial heat to heat the device to a certain degree of temperature to protect the chickens from exposure.

While I have shown and described the preferred embodiment of my invention, it will be understood that minor changes of construction, combination and arrangement of parts may be made without departing from the spirit and scope of the invention as claimed.

Having thus described my invention, what I claim is:—

A chicken brooder comprising a circular cover, means for supporting said cover in spaced relation to the ground, said cover having a central recess, a tuft of feathers secured within said recess, said cover having a plurality of circular arranged recesses in spaced relation to the central recess, tufts of feathers secured within said circular arranged recesses to form a passage way between the central tuft and the circular ar-

ranged tufts, a plurality of feathers secured to the periphery of the cover, and a metallic band secured to the periphery of the cover for securing and protecting the quills of the feathers secured to the periphery of the cover. 15

In testimony whereof I affix my signature in presence of two witnesses.

GUSTAVE JESSE.
